E. C. Phillips.

By Robert Burns Attorney.

UNITED STATES PATENT OFFICE.

ELWOOD C. PHILLIPS, OF CHICAGO, ILLINOIS.

DESIGN FOR A VEHICLE-WHEEL.

SPECIFICATION forming part of Design No. 31,683, dated October 17, 1899.

Application filed August 21, 1899. Serial No. 728,016. Term of patent 7 years.

To all whom it may concern:

Be it known that I, ELWOOD C. PHILLIPS, a citizen of the United States, residing at Chicago, in the county of Cook and State of Illinois, have invented and produced a new and original Design for Vehicle-Wheels, (Case A;) and I do declare the following to be a full, clear, and exact description of the same, reference being had to the accompanying drawings, forming a part of this specification.

This invention relates to a design for wheels for heavy wagons, trucks, and the like; and my said design consists in the structural configuration hereinafter described, and illustrated in the drawings.

In the accompanying drawings, illustrative of the present invention, Figure 1 is a side elevation, and Fig. 2 a view one-half in elevation and one-half in section.

As shown in the drawings, the web and hub portion of the wheel are formed by two counterpart plate members 4 and 5, each of which is formed with a flanged annular rim portion 6, which in turn comprises an outwardly-extended cylindrical portion at right angles to the main central web portion and an inwardly-extending plate portion, the periphery of which is formed with an inturned annular flange 7, that fits a concentric recess in the side of the wheel-tire.

One of the plate members above described is formed with the wheel-hub 9. The other plate member is formed hubless to fit over and bear upon the hub of the other member, as shown.

The completed wheel consists of the above-described web members and the tire member, the whole being fixedly and substantially attached together.

The outer portion 1 of the tire is of a substantially cylindrical form in cross-section, and the inner portion 2 of the tire is rectangular in cross-section, the two portions being integrally connected together by a central web 3, as shown, to leave at each side of the tire a concentric recess to receive the inturned marginal flange of the adjacent plate or web member heretofore described.

I claim—

The design for a vehicle-wheel, as herein shown and described.

In testimony whereof witness my hand this 14th day of August, 1899.

ELWOOD C. PHILLIPS.

In presence of—

ROBERT BURNS,
M. H. HOLMES.
